UNITED STATES PATENT OFFICE.

GEORGE C. LOCKLIN AND BONHAM M. FOX, OF CHICAGO, ILLINOIS.

WOVEN-WIRE FABRIC.

SPECIFICATION forming part of Letters Patent No. 655,253, dated August 7, 1900.

Application filed August 14, 1899. Serial No. 727,162. (No model.)

To all whom it may concern:

Be it known that we, GEORGE C. LOCKLIN and BONHAM M. FOX, citizens of the United States, residing at Chicago, in the county of Cook and State of Illinois, have invented certain new and useful Improvements in Woven-Wire Fabrics, of which the following is a specification.

This invention relates to improvements in woven-wire fabrics intended, primarily, to form springs for bed-bottoms, which fabrics have heretofore been necessarily handled by experts before the same are stretched upon and fastened to the frame, because of the extreme difficulty in preventing the fabric from unraveling. The fabric is made up of a series of parallel coils of wire interlaced with one another, part of the coils being generally formed of a number of wires and other and intermediate coils being formed of single wires; but all of the wires in the course of manufacture of the fabric are spirally wound. Hence when the ends of the wires forming the various strands are not properly held before being attached to a frame they not only spring longitudinally out of their relative positions in the fabric, so as to cause the separation and entanglement thereof, but by reason of their spiral winding they all bend and twist laterally in all directions, sometimes causing disintegration of the fabric. For these reasons not only are experts necessarily employed in handling the fabric, but when the fabric is put upon the market it is necessarily rigidly secured to the frames upon which it is to be permanently used generally by having the ends thereof fastened between the frame proper and a strip nailed along the edges of the frame or along the top side thereof. Hence there is considerable unnecessary expense in shipping the fabric when so stretched, due to the weight of the frame and the greater space occupied by the fabric when stretched upon the frame, which greatly increases the cost of transportation of the bed-springs, while at the same time requiring them to be permanently attached to a frame by the manufacturer of a spring. Furthermore, the present method of securing the springs to the frame by clamping the ends thereof with strips or batten of wood or metal is expensive and requires either the securing

of the strips or batten upon the upper surface or edge or in a rabbet made in the end rail of the frame. Furthermore, this method produces a fabric which varies materially in its tautness or elasticity at different points, which causes it to sag and become exceedingly uncomfortable after very short use, besides affording a hiding-place for bedbugs and vermin.

The primary object of our invention is to overcome and avoid all of these difficulties by providing a woven-wire fabric that can be handled by unskilled labor, that may be attached to any frame or support whenever and wherever desired, that may be safely transported unattached to any frame and at a much less cost than heretofore, and in which the ends of the strands are permanently secured as against the possibility of unraveling, while the least possible hiding-place for vermin is afforded. These and such other objects as may hereinafter appear are attained by the devices illustrated in the accompanying drawings, in which—

Figure 1 represents a plan view of a portion of a woven-wire fabric embodying our invention. Fig. 2 is an end elevation thereof. Fig. 3 is an enlarged sectional view of the same, and Fig. 4 is a detailed transverse section on the line 4-4 of Fig. 3.

Similar letters of reference indicate the same parts in the several figures of the drawings.

Referring now by letter to the accompanying drawings, A indicates the woven-wire fabric, which may be formed in any of the well-known and commonly-practiced methods or in any other desired way, as the formation of the fabric proper forms no part of our present invention. As shown in the drawings, the fabric is composed of a series of parallel strands B, composed of a number of coiled wires spaced a slight distance apart and connected by a pair of single-wire strands interposed therebetween, which single wires are interlaced with each other and with the strands B in the course of manufacture of the fabric, the single-wire strands being formed in coils of a diameter substantially equal to that of the plural-wire strands, so that the whole forms a fabric of substantially-uniform thickness. When the fabric is formed to the

desired length, the ends of the coils are pressed flat upon each other and inserted in the U-shaped metal strip C, as shown at the right-hand side of Fig. 3, so that the ends of all 5 the coils are secured and cannot become displaced. The U-shaped metal strip is then bent transversely upon itself, as illustrated at the left-hand side of Fig. 3, and the whole subjected to powerful compression, so that 10 the strip, with the ends of the strands inserted therein, will remain permanently in the form shown at the left in Fig. 3. The length of the metallic strips C will of course correspond substantially with the width of the 15 fabric, so as to properly, rigidly, and permanently secure the ends of the strands as against unraveling. After the fabric has the binding-strip secured to the end thereof and folded it is in condition for shipment without 20 being attached to a frame and will of course occupy the minimum space or, if desired, may be coiled. In this form the fabric may be shipped to the manufacturer of bed-bottoms and he may apply it to any frame de- 25 sired by simply nailing it through the binding-strips onto the frame, or where a metal frame is used it may be riveted or otherwise secured thereto. The expense of attaching such a fabric to the frame is therefore re- 30 duced to the minimum, and it can be easily done without the employment of expert labor and without requiring any special construction of the end rails or the employment of any cleat or batten or similar device. Ob- 35 viously the fabric so formed is equally adapted for use in bed-springs, in spring-cots, and in any other article of furniture where such a fabric can be employed, and the sheets of the fabric can be constructed specially of al- 40 most any desired shape or dimensions by the manufacturer of the fabric for subsequent attachment to the various articles of furniture by the manufacturer of the furniture, the mode of securing it to the article of fur- 45 niture being left to the selection of the user. The flattened ends of the coils inserted between the folds of the binding-strip practically fill the entire space between the folds of the strip and afford the least possible op- 50 portunity for the hiding or abode of vermin, and extensive practical use of the invention has demonstrated that a fabric so constructed is practically vermin-proof.

The binding-strip in our fabric has a three-fold function to perform—that of fastening or securing the ends of the coils as against unraveling or spreading, that of securing such ends in such a way as to withstand the great pressure to which a woven-wire fabric 55 is subjected in use as a bed-spring, and that of affording a means of firmly and securely fastening the fabric to a bed-frame. Such

fabrics when used for bed-springs are at-tached at their ends only to the bed-frame and are generally unsupported at interme-diate points, for which reason in the manu-fac-ture of such fabrics it is necessary to make 65 the coils of such strength that they will with-stand an endwise or stretching strain of from eight hundred to one thousand pounds, in 70 order to enable them to withstand the lateral strain to which they are subjected in use without sagging, and as sole reliance must be placed upon the means whereby the ends of the fabric are secured to the frame to pre- 75 vent the wires from drawing endwise from their attachment, and thereby becoming loose and sagging, it is of the utmost importance to have the fastening devices for the ends of the coils not only convenient for attachment 80 and of such character as to insure against the loosening or unraveling of the ends of the coils, but also so strong and secure as to prevent the ends of the coils from being pulled out in use. Our fabric as an article of manu- 85 facture combines all of these advantageous qualities in the maximum degree.

We are aware that wire-netting for window-screens and like purposes has been bound upon its edge, but not for the purpose of pre- 90 venting the unraveling thereof, because the wires of the netting are not coiled and have no tendency to unravel because of the man- 95 ner in which the wires are meshed. Neither are they bound for the purpose of our inven-tion, for the binding of the wire-netting is in-tended simply to afford a more secure and better finish to modes of attaching the netting to a frame, for the netting in transportation is invariably put up in rolls which is con- 100 venient and possible with a wire-netting, but would be impossible with a coiled woven-wire fabric, such as that contemplated by our in- 105 vention. Such prior devices are therefore not the same as our invention, are not in-tended for the same purpose, do not produce the same results, and are hereby disclaimed.

Having thus fully described our invention, what we claim, and desire to secure by Letters Patent, is—

As a new article of manufacture, a woven-wire fabric comprising woven coiled-wire springs having the ends thereof flattened to a common plane and bound by a metallic strip folded longitudinally so as to inclose 115 the flattened ends of the coiled strands of the fabric and then folded again upon itself, sub-stantially as described.
